DOLL MOUTH

Robert I. Prupis, Newton Centre, Mass., assignor to
Margon Corporation, Newark, N.J., a corporation of
New Jersey

Filed Sept. 14, 1956, Ser. No. 609,835
7 Claims. (Cl. 46—171)

This invention relates to toys, especially dolls, and more particularly to a simulated movable mouth therefor.

Attempts have been made to simulate a change in the facial expression of a doll by simulated movement at the mouth. This has required mechanical linkages or the like behind a mouth element disposed at a mouth opening.

Many doll heads are made of a soft, flexible material having a rather realistic skin-like surface. These heads may be molded inexpensively by slush molding a vinyl slurry in an outer mold, without requiring a core. The material is elastic enough to be pulled from the mold. It is usually stuffed later to help maintain its overall configuration.

The movable mouth mechanisms heretofore suggested are not suitable for use in flexible heads, and one primary object of the present invention is to provide a movable mouth mechanism for such heads.

Another object is to provide an operating mechanism which causes an instantaneous changeover from one mouth condition all the way to another, as the position of the head is changed, typically from an upright to a supine position. This unstable or total-change action simplifies the design and avoids the problem caused by intermediate positions of the movable element, which ordinarily may appear unrealistic or unnatural. Thus the artist need concern himself with only two terminal positions.

Still another object of the invention is to provide a movable mouth mechanism simulating a change of teeth, rather than a movement at the mouth. For this purpose, the mechanism includes an oscillatable element ornamented with differently delineated sets of teeth, one set of which is exposed and another set of which is concealed in one position of the element, and vice versa. Thus, one set may represent good teeth and the other bad teeth, and the toy may be used to encourage mouth hygiene by illustrating to a child the difference in appearance as between good and bad teeth.

To accomplish the foregoing general objects, and other more specific objects which will hereinafter appear, my invention resides in the mechanism for simulating a change of facial expression at the mouth of a doll, and the elements thereof, and their relation one to another and to the doll, as are hereinafter more particularly described in the following specification. The specification is accompanied by drawings, in which:

FIG. 1 is a front view of a doll head embodying features of the invention;

FIG. 2 is a section drawn to enlarged scale, and taken approximately in the plane of the line 2—2 of FIG. 1;

FIG. 3 is a similar view, but showing the relation of the parts when the head is turned from upright to supine position;

FIG. 4 is a section through the movable element;

FIG. 5 is a rear view of the movable element;

FIG. 6 is a side elevation of the assembled mouth mechanism which is later inserted in the doll head;

FIG. 7 is a front view of a doll head showing a modified and preferred form of the invention;

FIG. 8 is a transverse section taken approximately in the plane of the line 8—8 of FIG. 7;

FIG. 9 is a similar view but showing the relation of

2

the parts when the head is turned from upright to supine position;

FIG. 10 is a section through the movable element;

FIG. 11 is a side elevation of the assembled mechanism which is inserted in the doll head; and

FIG. 12 is a fragmentary section through the housing taken approximately in the plane of the line 12—12 of FIG. 11;

FIG. 13 is a section similar to FIG. 10, but showing a modified movable element.

Referring to the drawing, and more particularly to FIG. 1, I there show a flexible doll head H which is molded with a mouth opening O. The head is combined with mechanism, generally designated M, which simulates a change of facial expression at the mouth. In the particular case here shown the head H is also provided with eye openings 12 to expose eye members 14. These form no part of the present invention and require no further description. If movable their movement is independent of, and in no way linked to, the mouth mechanism.

Referring now to FIG. 2 of the drawing, the head H is molded with an integral socket 16 behind the mouth opening O. The mechanism M comprises a hollow thin walled casing 18, 20 which is dimensioned to be received in the socket 16. The casing has an opening 22 at the front which conforms generally to the mouth opening O. It may be made slightly larger in order to help conceal the edge of the housing material. The mechanism further comprises an oscillatable element 24 pivoted inside the housing on an axis indicated at 26, this element being partially exposed at the mouth opening O. It is moved by a weight member 30, best shown in FIGS. 4 and 5 of the drawing. This weight member is secured to and movable with the element 24 within the housing, and it serves to move the element between the position shown in FIG. 2 when the head H is upright, and the position shown in FIG. 3 when the head H is supine.

It is evident from the drawing that the movable element 24 is ornamented with simulated mouth parts some of which are exposed at the mouth opening O in one position, and concealed in another position of the element, thereby changing the facial expression of the doll. More specifically, in the present case the movable element 24 is ornamented with simulated teeth 32, 34 which are exposed in the mouth opening when the head is erect, as shown in FIG. 2, and which are concealed when the head is horizontal as shown in FIG. 3. Moreover, the movable element is preferably colored red in the area 36 below the teeth 34, this being in simulation of a lower lip. The region 38 below the part 36 is preferably flesh colored, this color is so far as feasible matching the flesh color of the head H in the region below the mouth opening. The effect is that when the head is erect, as in FIG. 2, the mouth appears to be open with the teeth showing, whereas when the head is in the horizontal position shown in FIG. 3 the mouth appears to be closed with the movable lower lip 36 adjacent the stationary upper lip 40, the red coloring for the latter being applied directly to an appropriately lip-shaped part of the doll's head at the top of the mouth opening.

In FIGS. 4 and 5 it is important to observe that the weight member 30 is disposed upwardly and forwardly of the pivot axis 26 when the head is erect. A consequence of this is that the movable element is unstable when the head is changed from vertical to horizontal position, so that the weight moves the element abruptly. When the head is tilted rearwardly a small amount, there is no corresponding change in the position of the movable element. When the head is tilted so far that the center of mass shifts from one side of the axis 26

to the other, the movable element swings all the way to its other extreme position instantaneously. It never assumes an intermediate position.

The opening movement, that is the position shown in FIG. 2, is preferably limited by stop means, here shown as an arm 42 which bears against the rear edge 44 of the forward part 18 of the housing. The closing movement, that is, to the position shown in FIG. 3, is limited by a stop means 46 which also bears against the rear edge 44 of the part 18 of the housing. In the present case the stop means 42 and 46 form parts of a metal stamping, the forward portion of which is embedded in the weight member 30. The movable member 24, the weight number 30, and the stop means are all assembled together in any desired fashion, as by cementing, mechanical interlock, or like expedient, so that these parts all turn in unison about the axis 26. The latter may be provided by a rod or pintle passing through the movable member and having its ends received in the side walls of the housing. The ends are preferably stepped or shouldered, as shown in FIGS. 2 and 3.

In the present case the housing comprises a forward part 18 and a rear part 20 which come together telescopically for a short distance, as is best shown in FIG. 2. The overlap may be limited by appropriate stops, here indicated by indentations at 48 best shown in FIG. 6. A small area at each side of the forward member 18 is preferably flattened, as shown at 50, and the flattened parts have bearing holes to receive the ends of rod 26. The rear part 20 of the housing is preferably provided with forwardly projecting ears 52 which are disposed outside the ends of the rod 26. These ears may be spaced outwardly somewhat from the surfaces 50, thereby providing clearance for the ends of rod 26.

A modified form of the invention is shown in FIGS. 7 through 12 of the drawing. Here again the head is a soft flexible head provided with a mouth opening 54 (FIG. 8) and a socket 56 behind the mouth opening. When the head is made by the so-called "slush molding process" the socket 56 comes out as a fully closed socket at the rear. The mechanism inserted in the socket again comprises a hollow thin walled casing 58, 60 with an oscillatable element 62 pivoted therein at 64, this element being partially exposed at the mouth opening. There is also a weight member 65, best shown in FIG. 10, and this weight member is disposed upwardly and forwardly of the axis 64 when the head is in erect position.

The present construction differs from that previously in a number of respects. One is that the forward part of the housing at the top edge of the mouth opening is bent or turned upward as shown at 66. This part is colored red and is suitably shaped to act as the stationary upper lip for the doll head. The latter is patterned or molded at the region 68 to receive or bear snugly against the back surface of the lip 66.

Another difference is that the movable element 62 includes a shaped part 70 which acts as the lower lip of the mouth. The part 70 is not only colored red, as before, but is shaped to simulate a lower lip. If desired, it may be stepped slightly, as indicated at 72, as though the forward tip of the tongue were visible. The part 74 below lip 70 is flesh colored, and the edge of the mouth opening at the bottom is tapered to a relatively thin edge, so that no lower lip is provided by the head itself.

A manufacturer making the mouth mechanism may supply the same as an assembled unit to the doll manufacturer, and with the present construction, the doll manufacturer does not need to apply any red coloring material for the lips or mouth. Instead the red for both upper and lower lips is already present at 66 and 70, and these reds, of course, may be made to match each other perfectly, as they should.

The part of the movable element above the lower lip

may be recessed rearward, and be shaped and colored white to simulate teeth, as indicated at 76. This simulates only the lower part of the upper teeth, and is visible when the head is erect, as shown in FIGS. 7 and 8.

5 However, when the head is tilted rearwardly to horizontal position as shown in FIG. 9, the movable element 62 changes to the position shown in FIG. 9, thus simulating closing of the mouth, for the lower lip 70 approaches the upper lip 66, and neither the teeth 76 nor the tongue 72 are visible. An increased part of the flesh colored area 74 becomes visible, and acts as a continuation of the lower part 78 of the head.

10 Another feature of the construction here shown is that the entire movable element is molded out of a single piece of material, typically one of the known plastics materials. The material is kept hollow and thin walled below the axis 64, as is indicated at 80 in FIG. 10. The material is filled in solidly above and forward of the axis 64, as is indicated at 65, and thus the solidly filled portion 65 acts as the weight member.

15 If desired, additional integral parts may be provided to act as stop means, and in such case the parts are thin walled and light in weight in order not to interfere with the desired action of the weight member 65. Thus in the present case a thin walled rearward extension 82 (FIG. 25) 10) may be used to limit the opening movement of the element 62, for it bears against the top rear portion of the housing, as is best shown in FIG. 8. Similarly the portion 84 may be employed as a stop means to limit 30 closing movement of the element, it bearing against the bottom of the housing, as shown in FIG. 9.

20 However, it will be understood that when the forward portion of the movable element is shaped, it may itself be appropriately dimensioned to act as motion limiting or stop means. Thus in FIG. 8 the portion 86 may bear against the bottom of the opening in the housing to limit the opening movement of the element 62, and in FIG. 9 the lip and/or tongue portion 70, 72 may bear against the top of the opening in the housing to limit the closing movement of the element 62.

25 As will be seen in FIGS. 8 and 11, the housing may consist of partially telescopic forward and rear portions, much as previously described. Thus the forward edge of the rear part 60 fits frictionally over the rear edge of the forward part 58, the motion being limited by stops or indentations shown at 88. The pivots 64 may be formed as 30 integral trunnions, and are received in bearing holes in flattened side portions 90 of the housing. The outer ends of the trunnions may be protected against frictional contact with the material of the doll head, by means of forwardly projecting ears 92, which may be stepped or displaced outwardly slightly, as shown in FIG. 12.

35 The trunnions may be put into the bearing holes by springing the side walls 90 apart slightly as, for example, by pressing the top and bottom parts of the forward housing 58 toward one another. The movable element 45 then is inserted forwardly through the open rear end of the housing part 58. The rear part 60 of the housing is added after the trunnions have been received in the bearing holes.

40 The doll is molded out of conventional soft materials in accordance with any usual practice. For example, the head may be molded out of soft rubber. However, it is more readily and economically made out of a vinyl slush molding compound, for with such compounds only an outside mold is needed, no inside core being required. The mouth opening and its socket are formed by providing a suitable plug in the mold. The plug is shaped and dimensioned to provide a socket which will snugly receive 45 and hold the housing, and also to provide a mouth opening which will substantially conform to the mouth opening of the housing. The material is sufficiently elastic and flexible to be pulled from a one-piece mold, the socket portion 56 being pulled from around the plug which forms the same. The elasticity of the material makes it possible

to insert the mouth assembly by simply forcing the same through the mouth opening into the socket.

The housing parts 58 and 60 are preferably formed of thin sheet metal. The movable element 62 is preferably molded out of a suitable plastics material, and the material is preferably flesh colored. In such case the only additional color to be applied is white at the teeth 76, and red at the lip and tongue 70 and 72. The flesh color at the area 74 is provided by the color of the plastics material itself. Other procedures may be used, as by painting the flesh color on a red plastic, etc.

It will be understood that while the movable element 62 simulates movement of a lower lip, it would be possible to provide stationary lower and upper lips, and to so design the movable element as to simulate the movement of a tongue only. In the resulting doll the mouth would remain open, but the tongue simulation would move.

In the present case the housing 58, 60 is made of sheet metal. The movable element 62 is made of a hard plastics material, the trunnions 64 being formed integrally therewith. However, the materials are not critical, and in the form of the invention shown in FIG. 4 the parts 24 and 30 may be made of metal, or the part 24 may be made of plastic while the part 30 is made of metal. In both forms of the invention the thin housing may be made of a hard plastics material instead of metal.

In the drawing, FIG. 2, 3, 6, 8, 9 and 11, the lower lip is lined vertically to indicate red, and in FIG. 11 the edge of the upper lip is similarly lined vertically to indicate red. In the specification the term "flesh color" has been employed, it being understood that this means external skin color. In a typical case the skin is fair, but may be of different colors to indicate different races.

It will also be understood that features of the first form of the invention may be interchanged with features shown in the second form of the invention. For example, in the latter I have shown the lip 66 formed integrally with the housing so that it is a part of the mouth mechanism applied to the doll head, whereas in the first form of the invention the upper lip is formed or painted directly on the doll head itself. It should be understood that the second form of the invention may be made as here shown, but omitting the upper lip 66, in which case the housing 58 terminates at the top within the mouth opening of the doll head, substantially as shown in the first form of the invention. While this has a disadvantage in requiring the doll manufacturer to color the upper lip of the doll head, it has the advantage of giving the doll manufacturer much greater leeway in originating the appearance and character of the doll face. Thus the artist designing the head may give the upper lip any desired configuration to help produce a desired expression on the doll head.

It will also be understood that the simulation of teeth at 76 on the movable element 62 may be omitted, in which case the action of the mouth mechanism will be to simulate opening or closing of the mouth by movement of the lower lip to the upper lip, but without showing teeth in either position. This change, and also the omission of rearward stop means, are shown in FIG. 13.

Referring to FIG. 13, the movable mouth element there shown generally resembles that shown in FIG. 10 in being molded out of a single piece of a hard plastic material, the piece as molded including trunnions 102. The part of the movable element forward and above the axis of trunnions 102, indicated at 100, is solid and thus acts as a weight. The region 108 below the axis 102 is preferably hollow and thin walled. In consequence the balance is unstable, and the element shifts abruptly between either of two positions corresponding to those shown in FIGS. 8 and 9. No rearwardly projecting stop means are provided, and instead the motion is limited by the forward or lower part of the movable element cooperating with the mouth opening in a manner which again may be seen from inspection of FIGS. 8 and 9.

In the form of the invention shown in FIG. 13 there are no simulated teeth. There is an indentation at 106

which may simulate the forward tip of a tongue. The areas at 104 and 106 are colored red. However, the bottom region of the movable element is flesh colored, much as previously described. This form of the invention simulates the opening or closing of the mouth by movement of the lower lip relative to the upper lip, but without attempting to simulate the showing of teeth.

With reference to the embodiment of FIG. 4, if desired, the movable member 24, weight member 30, the stop means, and the ends or trunnions at axis 26 may be integrally die cast of any suitable material to form a single unitary movable member, or the weight member 30, the stop means, and the ends or trunnions at axis 26 may be integrally die cast with such casting suitably united with member 24.

This application is a continuation-in-part of application Serial No. 544,854, filed November 4, 1955, and since abandoned.

It is believed that the construction and method of use of my improvement, as well as the advantages thereof, will be apparent from the foregoing detailed description thereof. It will also be understood that while I have shown and described the invention in several preferred forms, changes may be made in the structures shown, without departing from the scope of the invention, as sought to be defined in the following claims.

I claim:

1. Mechanism for simulating a change of facial appearance at the mouth of a flexible doll head having a mouth opening and a socket behind said mouth opening, said mechanism comprising a casing dimensioned to be received with a snug fit in the mouth socket of the head, said casing having an opening at the front conforming generally to the mouth opening, an oscillatable element pivoted in said casing to expose a surface area thereof to view at said mouth opening, a weight member disposed to be upwardly and forwardly of the pivot of said element when the head is erect, whereby the weight is unstable and is adapted to move abruptly when the head is changed from erect to supine position, and stop means to limit the motion of said movable element, said element having simulated mouth parts at said surface area some of which are exposed at the mouth opening of the doll in one position and concealed in another position of said element, said element being molded out of a single piece of material which is hollow and thin walled below the pivot and which is filled in solidly above and forward of the pivot when the head is in erect position, the said solidly filled in part constituting the weight member.

2. Mechanism for simulating a change of facial appearance at the mouth of a flexible doll head having a mouth opening and a socket behind said mouth opening, said mechanism comprising a casing dimensioned to be received with a snug fit in the mouth socket of the head, said casing having an opening at the front conforming generally to the mouth opening, an oscillatable element pivoted in said casing to expose a surface area thereof to view at said mouth opening, a weight member disposed to be upwardly and forwardly of the pivot of said element when the head is erect, whereby the weight is unstable and is adapted to move abruptly when the head is changed from erect to supine position, and stop means to limit the motion of said movable element, said element having simulated mouth parts at said surface area some of which are exposed at the mouth opening of the doll in one position and concealed in another position of said element, said element being molded out of a single piece of material which is hollow and thin walled below the pivot and which is filled in solidly above and forward of the pivot when the head is in erect position, the said solidly filled in part constituting the weight member, said element having additional integral parts constituting the stop means, said last mentioned parts being thin walled and light in weight in order not to interfere with the desired action of the weight member.

3. Mechanism for simulating a change of facial expression at the mouth of a flexible doll head molded with a mouth opening and an integral socket behind said mouth opening, said mechanism comprising a hollow thin walled casing dimensioned to be received with a snug fit in the mouth socket of the doll head, said casing having an opening at the front conforming generally to the doll mouth opening, an oscillatable element pivoted inside said housing and partially exposed at said opening, a weight member so located as to be disposed upwardly and forwardly of the pivots of said movable element when in a head which is erect, whereby the weight is unstable and is adapted to move abruptly when the head is changed from erect to supine position, stop means to limit the motion of said movable element, said movable element having simulated mouth parts some of which are exposed at the opening in one position and concealed in another position of the movable element, said casing having a forward part at the top edge of the mouth opening which is bent or turns upward and is shaped and colored red to act as a stationary upper lip for the doll head.

4. Mechanism for simulating a change of facial expression at the mouth of a flexible doll head molded with a mouth opening and an integral socket behind said mouth opening, said mechanism comprising a hollow thin walled casing dimensioned to be received with a snug fit in the mouth socket of the doll head, said casing having an opening at the front conforming generally to the doll mouth opening, an oscillatable element pivoted inside said housing and partially exposed at said opening, a weight member so located as to be disposed upwardly and forwardly of the pivots of said movable element when in a head which is erect, whereby the weight is unstable and is adapted to move abruptly when the head is changed from erect to supine position, stop means to limit the motion of said movable element, said movable element having simulated mouth parts some of which are exposed at the opening in one position and concealed in another position of the movable element, said casing having a forward part at the top edge of the mouth opening which is bent or turns upward and is shaped and colored red to act as a stationary upper lip for the doll head, and said element having a part which is shaped and colored red to act as a lower lip of the mouth, the part of said element below said simulated lower lip being flesh colored to match the color of the head.

5. Mechanism for simulating a change of facial expression at the mouth of a flexible doll head molded with a mouth opening and an integral socket behind said mouth opening, said mechanism comprising a hollow thin walled casing dimensioned to be received with a snug fit in the mouth socket of the doll head, said casing having an opening at the front conforming generally to the doll mouth opening, an oscillatable element pivoted inside said housing and partially exposed at said opening, a weight member so located as to be disposed upwardly and forwardly of the pivots of said movable element when in a head which is erect, whereby the weight is unstable and is adapted to move abruptly when the head is changed from erect to supine position, stop means to limit the motion of said movable element, said movable element having simulated mouth parts some of which are exposed at the opening in one position and concealed in another position of the movable element, said casing having a forward part at the top edge of the mouth opening which is bent or turns upward and is shaped and colored red to act as a stationary upper lip for the doll head, and said element having a part which is shaped and

colored red to act as a lower lip of the mouth, the part of said element below said simulated lower lip being flesh colored to match the color of the head, and the part of said element above said simulated lower lip being recessed rearward and shaped and colored white to simulate teeth.

6. Mechanism for simulating a change of facial appearance at the mouth of a flexible doll head molded with a mouth opening and an integral socket behind said mouth opening, said mechanism comprising a hollow thin walled casing dimensioned to be received with a snug fit in the mouth socket of the head, said casing having an opening at the front conforming generally to the mouth opening, an oscillatable mouth element pivoted inside said casing to expose a surface area thereof to view at said mouth opening, a weight member movable with said mouth element within said housing for moving said element between one position when the head is upright and another position when the head is supine, said movable element being ornamented at said surface area with simulated mouth parts some of which are exposed at the mouth opening in one position and concealed in another position of said element, the forward part of said casing at the top edge of the mouth opening being bent or turned upward and shaped and colored red to act as a stationary upper lip for the doll head, and said movable element including a part which is shaped and colored red to act as the lower lip of the mouth, the part of said element below said simulated lower lip being flesh colored to match the color of the head.

7. Mechanism for simulating a change of facial appearance at the mouth of a flexible doll head molded with a mouth opening and an integral socket behind said mouth opening, said mechanism comprising a hollow thin walled casing dimensioned to be received with a snug fit in the mouth socket of the head, said casing having an opening at the front conforming generally to the mouth opening, an oscillatable mouth element pivoted inside said casing to expose a surface area thereof to view at said mouth opening, a weight member movable with said mouth element within said housing for moving said element between one position when the head is upright and another position when the head is supine, said movable element being ornamented at said surface area with simulated mouth parts some of which are exposed at the mouth opening in one position and concealed in another position of said element, the forward part of said casing at the top edge of the mouth opening being bent or turned upward and shaped and colored red to act as a stationary upper lip for the doll head, and said movable element including a part which is shaped and colored red to act as the lower lip of the mouth, the part of said element below said simulated lower lip being flesh colored to match the color of the head, and the part of said element above said simulated lower lip being recessed rearward and shaped and colored white to simulate teeth.
